UNITED STATES PATENT OFFICE.

HENRY PRICE BALL, OF SCHENECTADY, NEW YORK, ASSIGNOR OF ONE-HALF TO SAMUEL INSULL, OF CHICAGO, ILLINOIS.

TRACKER-BOARD.

No. 804,822.

Specification of Letters Patent.

Patented Nov. 21, 1905.

Application filed November 20, 1903. Serial No. 182,087.

To all whom it may concern:

Be it known that I, HENRY PRICE BALL, a citizen of the United States, residing at Schenectady, county of Schenectady, State of New York, have invented certain new and useful Improvements in Tracker-Boards, of which the following is a specification.

This invention relates to tracker-boards of the type now commonly used in connection with a perforated music-strip on mechanical musical instruments; and it consists in a construction by means of which a tracker-board may be adjusted for use with music-strips of different width, of different scale, to change the key of a composition above or below that normal to the music-strip, and, further, in the means employed to overcome the objectionable noises due to friction of a paper music-strip in passing over the tracker-board, to 15 chattering or fluttering of the edges of the perforations in the music-strip when passing over the ducts in the tracker-board.

The objects of my invention are to provide means whereby any mechanical musical instrument may be used with any perforated music that can be purchased in the market and to generally improve the construction and mode of operation of mechanical musical instruments.

30 The accompanying drawings will serve to illustrate my invention.

Figure 1 is a transverse section on the line X X of Fig. 2. Fig. 2 is a vertical section on the line Y Y of Fig. 1. Fig. 3 is a plan view. Fig. 4 is an end view looking from the right, showing the frame for holding the movable portion of the tracker-board in its raised position. Fig. 5 is a section corresponding to Fig. 2, showing the first row of ducts in 35 the movable portion of the tracker-board in relation with the ducts in the fixed portion of the tracker-board. Fig. 6 is a section corresponding to Fig. 2, showing the last row of ducts in the movable portion of the tracker-board in relation with the ducts in the fixed portion of the tracker-board. Fig. 7 is a view corresponding to Fig. 1 and shows a modification of my invention as employed for 40 altering the key in which a composition is played. Figs. 8, 9, and 10 are vertical sections through Fig. 7 and show, respectively, the first, second, and third row of ducts in the movable portion of the tracker-board in relation with the fixed portion of the tracker-

board. Fig. 11 is plan view of Fig. 7. Figs. 55 12 and 14 represent transverse sections of a tracker-board or of the movable portion of a tracker-board provided with means for preventing chattering or fluttering of the paper of the music-strip as it passes over the tracker-board. Fig. 13 is a plan view of the top of one of the ducts shown in Fig. 12 with a portion of the music-strip passing through over it. Fig. 15 is a similar view having reference to Fig. 14.

60 In the drawings, 20 represents the body of a mechanical musical instrument of any well-known type and in which is mounted a tracker-board 21, the main ducts 22 in which communicate with the usual pneumatics through tubes 23. This tracker-board is located in the instrument in such a position that its curved upper surface 24 will be on the same level as the top of the arc-shaped plates 25, which plates may be separate or formed from 65 a part of the side frames of the instrument. Situated over the top 24 of the tracker-board and the arc-shaped plates 25 is a skeleton frame 26, slotted along its face or upper surface 27 or otherwise shaped to receive the 70 movable portion 28 of the tracker-board.

75 29 indicates cross-straps at the ends of the frame 26, which serve to hold the movable portion 28 of the tracker-board in place when inserted in the slot 27. The frame 26 is pivotally mounted at its opposite ends upon arms 30, pivoted at 31 to the side plates 25, and is also connected at its opposite ends to links 32, pivotally connected to cranks 33, also pivoted at 31 in the side plates. Mounted on the side 80 plates 25 back of the arms 30 are sectors 34, provided with holes 35. Mounted in each arm 30 is a pin 36, adapted to coact with the holes 35 in the sector 34 under it. Mounted also upon the arms 30 are the springs 37, which 85 exert an upward pressure upon the under side of the frame 26. The pins 36 coact with the holes 35 to hold the frame 26 in certain defined positions, as will hereinafter be described.

90 The movable portion 28 of the tracker-board may be perforated in any desired manner—that is, may be given any number of ducts or arrangements of ducts or character of ducts to coöperate when in relation with the main ducts 22 in the tracker-board 21.

100 105 In Fig. 3 three rows of ducts are shown, A B C, which I term "supplemental" ducts, and

for the purposes of description I will assume that the maximum number of perforations across the sheet of any commercial music-roll is thirty-three and the minimum number 5 twenty-nine. Such being the case, it will be seen that when the first row of supplemental ducts A is over the main ducts 22 all of such ducts will be operative, whereas if the second row of supplemental ducts B are over the main 10 ducts 22 but a portion of the main ducts will be operative. It will thus be seen that provision is made for two types of music-sheets, one having the largest number of perforations and the other having the smallest number of 15 perforations. Manifestly instead of having but two rows of supplemental ducts A B any number of parallel rows might be used.

Aside from there being in the market rolls having a greater or less number of perforations of uniform width and spacing arranged across the sheet there are music-rolls which carry a scale peculiar to themselves. Such a scale is indicated by the ducts C, where the ducts gradually decrease in width from the 25 sides of the sheet inwardly.

The relation of the supplemental ducts C to the main ducts 22 is shown in Fig. 6—that is, the ducts are inclined so as to bring them into relation with certain of the main ducts 30 22. It will be understood that when the supplemental ducts C are brought into relation with the main ducts 22 a music-sheet carrying a scale having perforations corresponding in position to the ducts C may be employed.

35 Instead of employing parallel rows of supplemental ducts of varying arrangement or character I may employ parallel rows of the same arrangement and character as shown in Fig. 11 and indicated as D E F. When 40 these supplemental ducts are brought into relation with the main ducts 22, the key in which the composition is played may be that in which it is written—*i. e.*, when the supplemental ducts E, Fig. 9, correspond with 45 the ducts 22—or may be transposed up the scale—*i. e.*, when the supplemental ducts D, Fig. 10, correspond with the main ducts 22 or down the scale when the supplemental ducts F, Fig. 8, correspond with the main 50 duct 22.

The fixed and movable portions of the tracker-board may be formed of any suitable material—such as wood, rubber, glass, metal—preferably any material which will hold its 55 form and which will not present a frictional surface to the moving music-strip. Glass I find to be very suitable for the purpose. Instead of using the materials mentioned from which to make the fixed and movable portions of the tracker-board I may make it (one or both portions) of paper or other material having the same coefficient of expansion and contraction under atmospheric conditions as the music-strip to be used with it. It will be 60 seen from the shape of the frame 26 that lon-

gitudinal expansion and contraction of the movable portion of the tracker-board, whatever material it may be made of, can freely take place within the frame.

I have stated that the tracker-board, both 70 portions, can be made of any of the materials mentioned. Of course it will be understood that the fixed portion of the tracker-board may be made of one material and the movable portion of another material. The frame 75 26 may carry a movable portion made of any material. This is an advantage—as, for instance, in dry weather I may use a movable portion made of wood, glass, or other material, and in wet or dry weather, when the 80 paper of which the music-strip is usually made is subjected to expansion and contraction, use a movable tracker-board made of paper or other material having the same coefficient of expansion and contraction as the 85 music-strip. With such a tracker-board I prefer to have the ducts formed in the movable portion and which register with the ducts in the fixed portion slightly larger at their ends where they coöperate with the ducts in 90 the fixed tracker-board, as shown in Fig. 5, than at the top where they coöperate with the perforations in the music-strip, as by so doing the expansion and contraction of the movable portion of the tracker-board may 95 take place without disturbing the coöperation between the ducts of the movable portion and fixed portion of the tracker-board.

In order to overcome the chattering sounds due to the vibration of the edges of the perforations in the music-strip in passing over the ducts, I may place over the ducts a series of fine parallel wires 38, Figs. 12, 13, or I may cover the surface of the removable portion 28 of the tracker-board by a body 39, (preferably an antifriction-body,) perforated over the ducts with a series of very fine holes 40, Figs. 14, 15.

It will be seen upon reference to Figs. 13 and 15 that the music-strip 41 in passing over 110 the supplemental ducts, which in all the figures I have indicated as *a*, is held flat—that is to say, the rear portion of the perforation *b* will be held down to the surface of the tracker-board and not drawn into the open 115 duct, as is now usual. When the edge of the perforation *b* is drawn into the duct, it chatters and by beating the side of the duct produces an objectionable noise, which is the purpose of perforations 40 to overcome.

The adjustment of the frame 26, carrying the removable portion 28 of the tracker-board, is effected by moving the arm 30 to the right or left, as required, and when the desired position is reached drawing the frame from the 125 position shown in Fig. 4 to the position shown in Fig. 1 and fixing it in such position by means of the link 32 and crank 33 and pin 36. The object of the spring 37 is to throw the frame into the position shown in Fig. 4 when 130

the tracker-board is not in use. Where the supplemental tracker-board is made of paper, it is desirable, in order that the paper shall be uniformly exposed on both its surfaces to 5 the action of the atmosphere, to hold it when not in use in an elevated position.

I wish it understood that I do not limit myself to the various details of construction illustrated and described in this application, as it 10 will be evident that very many modifications can be made without departing from the intent of my invention.

Having thus described my invention, I claim—

15 1. A tracker-board comprising a fixed portion having a series of ducts, and a portion movable relative to the fixed portion having a plurality of series of ducts, differently spaced at one surface of the movable portion and 20 each series adapted to coact with the ducts of the fixed portion when moved into relation therewith.

2. A tracker-board comprising a fixed portion having a series of ducts, and a portion 25 movable relative to the fixed portion having a plurality of series of ducts differing in size, each series adapted to coact with the ducts of the fixed portion when moved into relation therewith.

3. A tracker-board comprising a fixed portion having a series of ducts, and a portion 30 movable relative to the fixed portion having a plurality of series of ducts differing in direction in such movable portion, each series 35 adapted to coact with the ducts of the fixed portion when moved into relation therewith.

4. A tracker-board comprising a fixed portion having a definite number of ducts, and a 40 movable portion having a plurality of series of ducts, one series corresponding in number with the ducts in the fixed portion, one series less in number, and one series of different shape, each series adapted to coact with the ducts of the fixed portion when moved into 45 relation therewith.

5. A tracker-board comprising a fixed portion having a definite number of ducts, a pivoted frame, a movable portion formed of a material whose coefficient of expansion and 50 contraction will be the same as that of the music-strip to be used in connection with it, and having a plurality of series of ducts, each series adapted to coact with the ducts of the fixed portion when moved into relation there- 55 with.

6. A tracker-board comprising a fixed portion having a definite number of ducts, a pivoted frame, a movable portion having an antifriction-surface mounted in said frame.

60 7. A tracker-board comprising a fixed portion having a definite number of ducts, a pivoted frame, a movable portion mounted in said frame and having a plurality of series of ducts with the openings of said ducts protected to 65 prevent entrance of the paper of the music-

strip used with the tracker-board into the ducts, and each series adapted to coact with the ducts of the fixed portion when moved into relation therewith.

8. A tracker-board comprising a fixed por- 70 tion having a definite number of ducts, a frame movable in relation to the fixed portion, a movable portion mounted in said frame and having a plurality of series of ducts, each series adapted to coact with the ducts of the 75 fixed portion when moved into relation therewith, together with means for fixing said frame in certain defined positions.

9. A tracker-board comprising a fixed por- 80 tion having a definite number of ducts, a frame movable in relation to the fixed portion, a movable portion mounted in said frame and having a plurality of series of ducts, each series adapted to coact with the ducts of the 85 fixed portion when moved into relation therewith, together with means for lifting the frame and the movable portion out of coöperative relation with the fixed portion.

10. A tracker-board comprising a fixed por- 90 tion, having a definite number of ducts, a mov- able portion formed of a material which will have the same coefficient of expansion and contraction as the paper strip to be used there- 95 with, and having a plurality of series of ducts, each series adapted to coact with the ducts of the fixed portion when moved into relation therewith, together with means for adjusting the position of the movable portion relative to the fixed portion.

11. A tracker-board having a series of ducts 100 therein, and means situated at the upper openings of the ducts which will prevent the entrance of the paper of the music-strip into the ducts as it is drawn across the ducts.

12. A tracker-board comprising a fixed por- 105 tion having a series of ducts, a movable portion having a plurality of series of differently- spaced ducts, and means for moving said last- named portion into and out of relation with the fixed portion.

13. A tracker-board comprising a fixed por- 110 tion having a series of ducts, a movable portion having a plurality of series of ducts, and means for moving said movable portion into and out of relation with the fixed portion and for elevating said movable portion to allow 115 access of air to its under side.

14. A tracker-board comprising a fixed por- 120 tion having a series of ducts, a pivoted frame, a movable portion carried by said frame and removable therefrom, said movable portion having a plurality of series of differently- spaced ducts, each series adapted to coact with the ducts of the fixed portion when moved into relation therewith.

15. A tracker-board comprising a fixed por- 125 tion having a definite number of ducts, a por- tion movable in relation to said fixed portion and having a plurality of series of ducts, one series vertically disposed therein and the other 130

- two series angularly disposed therein, each of the series of ducts of the movable portion adapted to coact with the ducts of the fixed portion when moved into relation therewith.
- 5 16. A tracker-board comprising a fixed portion having a series of ducts, a pivoted portion having a plurality of series of differently-spaced ducts arranged in parallel rows, and each series adapted to coact with the ducts of the fixed portion when brought into relation therewith.
- 15 17. In combination with a music-strip having a definite number and arrangement of perforations, a tracker-board comprising a fixed portion having a series of ducts, and a movable portion having a plurality of series of differently-spaced ducts, said movable portion interposed between the music-strip and the fixed portion and adapted to establish coactive relation between the perforations in the music-strip and the ducts in the fixed portion of the tracker-board.
- 20 18. A tracker-board comprising a portion having a series of ducts, and a superposed portion having a number of differently-spaced ducts for each duct in the lower portion.
- 25 19. A tracker-board comprising a main portion, and a supplemental detachable portion formed of a different material.
- 30 20. A tracker-board comprising a fixed portion, a superposed removable portion, and means for holding such portions separated when not in operation.
- 35 21. A tracker-board comprising a fixed portion having a series of ducts, and a movable portion having a plurality of series of inclined ducts.
- 40 22. A tracker-board comprising a fixed member having a series of ducts, and a movable member having a plurality of series of ducts, said ducts being similarly spaced upon the under side of the movable member, so that they will correspond in spacing with the ducts in the fixed member of the tracker-board, and 45 dissimilarly spaced upon the upper side of the movable member.
- 45 23. A tracker-board comprising two portions, one pivoted to the other, and each provided with ducts, the center distances between 50 ducts in one section equally spaced and in the other section unequally spaced.
- 50 24. A tracker-board comprising a fixed portion having a series of ducts therein, a movable portion having a plurality of series of 55 diagonally-disposed ducts therein.
25. A tracker-board comprising a fixed portion having a single row of equally-spaced ducts, and a superposed movable portion having a plurality of rows of ducts, one row differing from the others as to the scale scheme 60 of center distances between the ducts.
- 65 26. A tracker-board comprising a fixed portion, a frame pivoted thereto, and a removable supplemental portion carried by said frame.
- 70 27. A tracker-board comprising a fixed member having equally-spaced ducts, and a superposed movable portion having a row of ducts with orifices at unequal distances between centers.
- 75 28. A tracker-board consisting of several members coacting to form a row of continuous ducts when in service, and means for holding the members apart when not in service.
- 80 29. A tracker-board comprising a portion having a series of ducts arranged according to a given scale, and a portion coacting with said first-named portion and having a plurality of series of ducts arranged according to two different scales.
- 85 30. A tracker-board comprising a fixed portion having a series of ducts arranged according to a given scale, and a movable portion having a plurality of series of ducts, each arranged according to a different scale, together 90 with means for adjusting any series of ducts in the movable portion relative to the ducts in the fixed portion.
- 95 31. A tracker-board divided into two sections, a series of equally-spaced ducts in the lower section, and a plurality of series of variously-spaced ducts in the upper section, together with means for adjusting any series of ducts in the upper section relative to the series of ducts in the lower section.
- 100 32. A tracker-board comprising a fixed portion having a series of ducts, and a movable portion having a plurality of series of ducts, said ducts having their inlets and orifices differently spaced and arranged in parallel rows in the top and bottom of the movable portion, and said duct-orifices spaced to coact with the ducts in the fixed portion.

In testimony whereof I affix my signature in the presence of two witnesses.

HENRY PRICE BALL.
